UNITED STATES PATENT OFFICE

135,853

DESIGN FOR LATTICEWORK

Lewis W. Cohn, Chicago, Ill.

Application March 4, 1943, Serial No. 109,664

Term of patent 7 years

To all whom it may concern:

Be it known that I, Lewis W. Cohn, a citizen of the United States, residing at Chicago, in the county of Cook and State of Illinois, have invented a new, original, and ornamental Design for Latticework, of which the following is a specification, reference being had to the accompanying drawing forming a part thereof.

In the drawing,

Figure 1 is a fragmentary perspective view of the latticework, showing my new design; and

Fig. 2 is a front elevational view thereof.

I claim:

The ornamental design for latticework, substantially as shown.

LEWIS W. COHN.
